LA FAYETTE LOUIS, OF NEW YORK, N. Y.

Letters Patent No. 88,967, dated April 13, 1869.

MELODEON ATTACHMENT FOR PIANO-FORTES.

The Schedule referred to in these Letters Patent and making part of the same.

To all whom it may concern:

Be it known that I, LA FAYETTE LOUIS, of the city, county, and State of New York, have invented a new and improved Melodeon-Attachment for Piano-Fortes, and other suitable fixtures, and that the following description, taken in connection with the accompanying drawings, hereinafter referred to, forms a full and exact specification of the same, wherein I have set forth the nature and principles of my said improvement, by which my invention may be distinguished from all others of a similar class, together with such parts as I claim, and desire to have secured to me by Letters Patent.

This invention relates to a new and improved removable melodeon-attachment for piano-fortes and other suitable fixtures, such as tables, &c.

The principal object of the invention, however, is to obtain a means whereby a melodeon, its bellows, and other necessary fixtures, may be readily attached to a piano-forte, and applied in such a manner that the two instruments may be played upon simultaneously, a bank of keys being in convenient position for each hand, or either instrument played upon separately, or the two played upon alternately, the two instruments, although connected, being entirely independent of each other, so far as their internal arrangement, or the construction of their musical producing-parts is concerned.

In the accompanying sheet of drawings—

Figure 1 is a plan or top view of my invention, applied to a piano-forte.

Figure 2, an inverted plan of the same.

Figure 3, a transverse section of the same.

Similar letters of reference indicate corresponding parts in the several drawings.

A represents the body of the piano-forte, which may be made in the usual manner.

B represents the legs.

These parts, being of usual construction, do not require a prolix description.

D represents a melodeon, which is constructed substantially in the usual way, E representing the keys, and F representing flat tubes, all of which communicate with each other, two of which, *a a*, are parallel with each other, and are fitted or work between cleats *b b*, secured to the under side of the body A of the piano-forte.

The tubes F, besides supporting the melodeon in position, or connecting it to the piano-forte, also serve to form a communication between the bellows G and the body of the melodeon, as will be fully understood by referring to fig. 3, an elastic or flexible tube, c, forming the connection between the bellows G and the tubes F.

The bellows is constructed in the usual way, and is fitted between cleats *d d* at the under side of the body

A of the piano-forte, like the melodeon D, as will be fully understood by referring to fig. 3.

The bellows is operated by a treadle or pedal, H, which is fitted in the lower part of a standard, I, so arranged as to be movable or adjustable, that the treadle or pedal may be brought within the reach of the foot of the operator, or player. This will be fully understood by referring to fig. 2.

From the above description, it will be seen that the melodeon-attachment and its bellows may be readily applied to and detached from the piano-forte without marring any part of its case, and by a very simple arrangement of means; and that there are also two banks of keys, each bank having its appropriate mechanism, one being perfectly independent of the other, and still the two banks of keys having such a position that both instruments may be played upon simultaneously by one and the same performer, or either played upon separately, as may be desired.

The melodeon is directly in front of the piano-forte keys; that is to say, the keys C of the latter are directly behind the keys E of the former, as shown clearly in fig. 1. The usual swells and stops may be applied to the melodeon, and operated in the usual way, and do not conflict with the free use of the ordinary pedals of the piano-forte.

I wish it to be distinctly understood that I do not claim broadly the combining of the two instruments, the piano-forte and melodeon, irrespective of the manner of combining them, for the above-named instruments have been combined, but in a way entirely different from mine, herein shown and described. In the first place, the two instruments have been combined so that one and the same bank, or set of keys would answer for both instruments; and, in the second place, the two instruments have been combined so as to have two separate banks, or sets of keys, but still so arranged or placed that the two sets, or banks of keys could not be played upon simultaneously, or at the same time by the same person. Neither could said attachments be removed from the piano, leaving said piano intact, or be added, without constructing the piano-case expressly for such purpose.

Having thus described my invention,

I claim as new, and desire to secure by Letters Patent—

1. The combination, with a piano-forte, of an adjustable and removable musical wind-instrument, provided with melodeon-reeds, key-board, and bellows, complete in itself, when placed in front of the piano-keys in such position as to enable one and the same performer to play upon both instruments either separately, alternately, or simultaneously, substantially as set forth.

2. A separate and distinct musical instrument, complete in itself, when so constructed as to admit of its

being attached to any style of piano-forte without the necessity of cutting or altering either instrument.

3. The adjustable standard for supporting the pedal *H*, arranged substantially as and for the purpose set forth.

4. The attaching of a wind-instrument, provided with melodeon-reeds and separate key-board and bellows to a piano-forte, by inserting or fitting the melodeon and its bellows between suitable cleats attached to the under side, or bottom of the body of the piano-forte, substantially as shown and described.

5. The flat tubes *F*, when applied to the melodeon, and arranged substantially as shown and described, to admit of the melodeon being firmly secured to the piano-forte, and also admit of a communication being formed between the bellows *G* and the melodeon *D*, substantially as shown and described.

LA FAYETTE LOUIS.
